(57) **CLAIM**

The ornamental design for a protective sleeve for a trailer hitch, as shown and described.

DESCRIPTION

FIG. 1 is a perspective view of the protective sleeve for a trailer hitch showing my new design;

FIG. 2 is a top plan view thereof;

FIG. 3 is a bottom plan view thereof;

FIG. 4 is a right side elevation view thereof;

FIG. 5 is a left side cutaway view thereof;

FIG. 6 is a left side elevation view thereof;

FIG. 7 is a front elevation view thereof; and,

FIG. 8 is a rear elevation view thereof.

Broken lines are included for depicting environmental subject matter and form no part of the claimed design.
